PIPE COVERING

Filed Nov. 24, 1928

Charles J. Wissner
ATTORNEY.

UNITED STATES PATENT OFFICE

LEWIS M. RISHEL, OF DETROIT, MICHIGAN

PIPE COVERING

Application filed November 24, 1928. Serial No. 321,556.

This invention relates to pipe covering and the object of the invention is to provide a covering for insulating pipe lines which may be readily secured to or removed from a pipe with a minimum of trouble and inconvenience.

Another object of the invention is to provide a pipe covering for use in connection with a resilient compressible insulating medium in which the insulating medium is compressed within a casing when positioned on a pipe and the resiliency of the insulating medium is utilized to hold the casing in position on the pipe.

15 A further object of the invention is to provide a pipe covering having a sheet metal outer casing provided with interlocking flanges at the edges to adapt it when interlocked to compress the insulating material 20 between the covering and the pipe and by this compression to maintain a tension on the cover to hold the flanges in interlocked relation.

These objects and the several novel features of the invention are hereinafter more fully described and claimed and the preferred form of construction by which these objects are attained is shown in the accompanying drawings in which—

25 Fig. 1 is an elevation of a pipe covering embodying my invention.

Fig. 2 is a section taken on line 2—2 of Fig. 1.

Fig. 3 is a section showing the pipe covering being applied to a pipe.

Fig. 4 is a section showing the method of securing the pipe covering in position.

This invention is designed for use with mineral wool on account of its high insulating qualities and the fact that it is resilient and compressible. The mineral wool may be used in its raw state but is preferably felted in blocks for use in this device.

The usual method of applying mineral wool to pipe lines is to use the mineral wool felted in blocks and wrap it around the pipe which is then covered with a wire mesh secured about the mineral wool to hold the mineral wool in place on the pipe. After 50 this has been done a coating of plaster is

laid over the wire mesh and after the plaster has dried it is covered or wrapped with fabric which is given two coats of paint before the installation is completed. While efficient results are attained in this manner it is impossible to produce a smooth and even contour on the finished pipe covering. Another disadvantage is due to the time lost in applying this type of covering to the pipe as it is necessary to wait until the plaster coat has dried before the covering is wrapped on and after the covering is wrapped and a coat of paint is applied it is necessary to wait for the paint to dry before a second coat may be applied. Another disadvantage is due to the fact that considerable of the paint soaks into the covering and thus an excessive quantity of paint is utilized.

In my invention the pipe covering is made up in sections and may be applied to the pipe in end to end relation along the pipe lines being covered and the joints between the sections may be covered with a thin metal strap at which time the entire covering may be given a single thick coat of paint which covers the covering and the installation is completed at one time without requiring the return of the workers to complete or finish the job. My device, as shown in Fig. 3, consists of a piece of sheet metal 1 which is first bent to substantially U shaped form as shown in Fig. 3. This member 1 is provided with return bent edge flanges 2 and 3. The felted block 4 of mineral wool is then applied to the inside of the member 1 with an adhesive at which time the device is ready for installation.

To install the device it is positioned about the pipe line 5 in the manner shown in Fig. 3 and the edges 2 and 3 are turned inwardly to the position shown in Fig. 4 and sufficient mineral wool is provided on the felted block so that it is necessary to compress the mineral wool about the pipe to bring the flanges 2 and 3 to overlapping position. When this has been done, by means of special pliers as shown in Fig. 4, the inherent resiliency of the compressed mineral wool tends to expand the casing 1 and causes the flanges 2 and 3 to interengage as shown in Fig. 4.

As the mineral wool always retains its resiliency a constant pressure is maintained on the outer casing 1 at all times tending to hold the interlocking flanges 2 and 3 in engagement. The pipe covering comes in different lengths and the different sections are installed in end to end relation throughout the length of the pipe. Each section of the covering 1 is notched out at 6 where the flanges 2 and 3 come together and when the sections are positioned in abutment the notches provide a space for the thin metal strap 7 which is utilized to cover the joint. One end of the strap is provided with a link 8 secured thereto and the opposite end of the strap is inserted through this link and bent over as shown to cover the joint 9. The sheet metal casing 1 is preferably made of galvanized sheet metal and after the covering has been installed as shown in Fig. 1 a heavy coat of paint is applied to the cover and the installation is completed. Due to the metal casing the paint will not soak into the cover and thus only a single coat of paint is needed to cover. In this manner the installers may install the covering and give it its final coat of paint thus completing the installation at one time and eliminating the necessity of returning to the job two or more times to complete the finishing steps as has been heretofore required. It is also possible to cut the covering with a pair of tin shears to meet special situations or when odd lengths of pipe covering are required and the installation when completed presents a smooth even surface and finish that cannot be excelled. The casing when installed in this manner is in itself waterproof and fireproof as well as the insulating material within the casing.

As will be understood from Fig. 4 the special pliers may be used for removing the pipe covering. By forcing the ends of the pliers inwardly to compress the casing and insulating material the flanges 2 and 3 may be readily disengaged at which time the covering may be readily removed from the pipe and used again. With the ordinary construction if it is necessary to move a pipe the pipe covering is torn off and thrown away and a new covering is put on. With my pipe covering the pipe covering may be removed and the pipe moved and the covering may be again replaced on the pipe without impairing its efficiency to the slightest degree.

While I have described this invention as used for pipe covering it will be understood that it can be used in the larger sizes for covering range boilers, tanks or in fact any substantially round device that requires an insulating cover.

From the foregoing description it becomes evident that the device is very simple and efficient in operation, will not easily get out of order, may be very easily installed or re-

moved from a pipe and provides a device which accomplishes the objects described.

Having thus fully described my invention, its utility and mode of operation, what I claim and desire to secure by Letters Patent of the United States is—

1. A device of the character described comprising a sheet metal casing cylindrical in form having two edges and adapted for interlocking relation, a resilient and compressible lining, such as felted mineral wool, secured to the casing by cementing the outer surface of the lining member thereto, the arrangement providing that in placing the device about a member to be insulated the lining directly engages the member and by reason of its resilient and compressible characteristics permits the edges of the sheet metal casing to be interlocked and maintained under tension by the lining.

2. As a new article of manufacture, a pipe covering manufactured and sold to the trade in the form of a sheet of metal of the desired length and width, the opposite edges of which are return-bent, and a resilient and compressible insulation secured to the casing and the whole bent to U form with the metal sheet on the exterior of the article, the said edges being adapted to be interlocked in assembling the device on a pipe or the like by folding the legs of the U together to thereby place the lining under compression and hold the said interlocked edges in tension.

In testimony whereof I sign this specification.
